Attorney

UNITED STATES PATENT OFFICE.

HANS BERGGRAF, OF STAVANGER, NORWAY.

OPENING DEVICE FOR TINS AND SHEET-METAL BOXES.

1,210,139.

Specification of Letters Patent. Patented Dec. 26, 1916.

Application filed June 1, 1916. Serial No. 101,046.

To all whom it may concern:

Be it known that I, HANS BERGGRAF, engineer, citizen of Norway, residing at Eilert Sundts Gate 22, Stavanger, Norway, have invented new and useful Improvements in Opening Devices for Tins and Sheet-Metal Boxes, of which the following is a specification.

The present invention has for its object to provide an opening device for tins, cans and sheet metal boxes.

According to this invention the opening tongue, its substitute or the part holding it fast and which is gripped and coiled up by the key, is formed from the material of the can cover, so that the use of solder is not necessary and the tongue need not be folded into the folding seam connecting together the can body and cover.

The invention is illustrated in the accompanying drawing, in which—

Figure 1 is a longitudinal section of a can or box cover showing the first stage of the formation of the tongue or of the part holding it fast. Figs. 2-5 show different forms of execution. Figs. 6-8 show another form, Fig. 6 being a longitudinal section of the can cover in the first stage of the formation of the tongue, Fig. 7 being a section through the finished cover, the opening key being placed in position, and Fig. 8 being a section of the opening tongue or rip drawn to a larger scale.

The cover —1—, which has been pressed in the die in usual manner, has for the most part the ordinary shape comprising middle portion —2—, side portions —3— and folding rim —4— as shown in Fig. 1, but the cover differs from the ordinary shape in that the middle portion —2— is provided with a member —5— near one edge, this member being also pressed up in the die. The cover is then laid into a special machine, in which the bulb —5— has opposite walls folded against each other. During this operation the bulb may be compressed in such a manner that it holds fast the doubled inner portion —11— of the ordinary loose, opening tongue —10—. The member 5 may also itself constitute the

opening tongue as indicated at —12— in Fig. 3, and in such case this tongue is preferably provided with a thickened portion obtained for instance by doubling the material as shown at —13—. Finally the doubled portion may be bent to one side (14 in Fig. 4) or as shown at 15 in Fig. 5.

According to the Figs. 6-8 the member —5— is compressed so as to form an upwardly projecting rib or rail of about T-shaped cross section. When a key —7— having the cross section shown in Fig. 7 is applied over the top of the rib —6— and is then turned, the sheet metal cracks at —8— or —9— (Fig. 8), whereafter the opening is continued along weakened lines in ordinary manner. In order to cause the rib —6— to be easily separated just at the desired place —8— or —9— from the remaining material, a weakening is made by pressing at this place as indicated in Fig. 8. This weakening may be made simultaneously with the formation of the rib —6—.

Having now described my invention, what I claim as new and desire to secure by Letters Patent is:

1. In a sheet metal receptacle having a wall provided with a weakened, tearing portion integral therewith, an outwardly projecting gripping member integral with said tearing portion and including side walls folded against each other.

2. In a sheet metal receptacle having a wall provided with a weakened, tearing portion integral therewith, a projecting, gripping member formed integral with the said tearing portion and having in itself a weakened part connecting it with the strong part of the said receptacle wall.

3. In a sheet metal receptacle having a wall provided with a weakened, tearing portion integral therewith, an outwardly projecting gripping member integral with said tearing portion and including side walls folded against each other, said member itself being weakened along a line of its fold.

In testimony whereof I have signed my name to this specification in the presence of two subscribing witnesses.

HANS BERGGRAF.
